MARKER FOR TROUSER CUFFS

Joseph Sabatini, Flushing, N. Y.

Application November 29, 1950, Serial No. 198,191

2 Claims. (Cl. 33—2)

This invention pertains to a measuring device, and, more particularly to a tailor's measure for determining desired lengths of wearing apparel.

One object of the invention is the provision of mated measuring and marking appliances designed for facilitating the measuring of the length of trousers and the cuffs thereof and the folding of the cuff portion to provide the proper trouser length in the finished garment.

Another object of the invention is to construct the said mated appliances in such manner that the one is utilized without the slightest discomfort to the fittee to mark a trouser leg at an arbitrarily fixed distance from the floor, and the other by alignment with the marking is precisely positioned for marking the exactly correct fold lines for the cuffs of the trousers.

A further object of the invention is to provide for adjusting the first said appliance to mark the trousers at a point closer to or further from the floor to accommodate persons who do not desire their trouser cuffs to be located at what is generally considered to be the fashionable height above the floor.

Still another object of the invention is to construct the first said appliance in such manner that the same is also utilizable for marking the hem lines of ladies' skirts and the cuff line of boys' trousers.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of one of the appliances of the invention.

Fig. 2 is a side elevational view of said appliance.

Fig. 3 is a fragmentary rear view of the appliance.

Fig. 4 is an enlarged sectional view on line 4—4 of Fig. 3.

Fig. 5 is a plan view of the other appliance of the invention, a portion thereof being broken away to conserve space.

Fig. 6 is a side elevational view of the appliance of Fig. 5.

Fig. 7 is a diagrammatic sectional view illustrating the formation of a full trouser cuff.

Fig. 8 is a diagrammatic view similar to Fig. 7 but illustrating the formation of an imitation or French cuff.

It is deemed desirable to describe the details of

construction of both appliances of the invention before attempting to describe the function of either. Referring to Figs. 1—4, there is illustrated a standard 10 which comprises a foot piece 11 surmounted by a rectangular bar 12 having one broad face aligned with the high end of foot piece 11. Preferably the foot piece 11 and bar 12 are formed of hardwood. At its upper end the bar 12 tapers slightly in width and is provided in each side edge with upper and lower notches 13, said notches being located the same distance apart vertically as the upper one is spaced below the flat upper edge of the bar.

Extending downward from the upper edge of bar 12 is a wedge-shaped groove 14 having the narrow side thereof open to the rear face of the bar. Mounted in the said groove for sliding movements up and down is a wedge-shaped block 15 whose upper edge is normally aligned with the upper edge of the bar. One side edge of bar 12 is notched to receive a cover plate 16 for a vertical groove 17 in the said notched edge, said plate being held in place by suitable screws 18. Near its upper end plate 16 and bar 12 are provided with aligned short vertical slots 20 through which a wing head screw 21 passes into the lower end of block 15 in which it is threaded. Screw 21, it will readily be seen, effectively locks block 15 in any desired vertical position. Below the slot 20 plate 16 is provided with a long vertical slot 22 through which passes the shank of a bolt 23 having its head located in the groove 17 and having a cylindrical nut-like handle 24 threaded on its outer end. The handle 24 is locked in any desired vertical position by drawing the same up on bolt 23 against plate 16. Located in the front face of bar 12 is a horizontal groove 25 which extends also across one side edge of the bar, said groove being identified by the letter B. Other identifying letters S for shorter and L for longer are situated alongside of arrows 26 imprinted on the front face of bar 12 near the upper end thereof and pointing upward and downward, respectively.

The cooperating appliance of the invention is illustrated in Figs. 5 and 6 and comprises a T-shaped template 27 of plastic or fibre board or the like. At the juncture of the upright and the cross bar of the template the upright is provided at either edge with a notch 28. As shown, the upright of the template is inclined somewhat so that the free end thereof is located a short distance forward of its juncture with the cross bar. Also, the under edges of the cross bar incline away from the notches 28. The far edge 29 of the cross bar and also the free edge of the up-

right are at right angles to a perpendicular between the two. A lateral slot 30 is located in the cross bar of the template and the edge 31 thereof nearest the notches 28 is located equidistant between said notches and the distant edge 29 of the cross bar.

Men's trouser cuffs generally are formed as shown in Fig. 7. The material 33 of the trouser leg is turned up at 34 which point determines the lower edge of the cuff, extends upward to 35 where it is turned downward again, point 35 forming the upper limit of the cuff, and then extends downward to 36 around the point 34, and ends within the trouser leg a short distance above point 36. The distance between points 34 and 35 and 36, that is, the vertical dimension of the cuff, is the same in all but a few instances; and the distances between the notches 28 and the slot edge 31 and between the latter and the far edge 29 of the cross bar of the template are made equal thereto. Therefore, if the template is laid on a trouser leg and chalk marks are made at the notches 28 (for fold 34) the edge 31 (for fold 35) and the edge 29 (for fold 36), a perfect cuff will result when the material is folded at the chalk lines.

It is not only necessary to form a perfect cuff, but it is also necessary to locate the under edge 34, 36 of the same at the proper distance above the floor when the trousers are worn. This is accomplished as shown in Figs. 2 and 5. The person on whom the trousers are being fitted stands alongside the standard 10 and a chalk mark 37 is made on the trouser leg 38 in alignment with the upper edge of bar 12. In forming the cuffs of the trousers, the end edge of the upright of template 27 which may conveniently be provided with a notched corner to indicate the forward end thereof is aligned with the chalk mark 37 before making the above-described cuff fold marks. The length of the upright of the template between the notches 28 and the end edge thereof is shorter than the height of the upper edge of bar 12 above the ground by a distance equal to the amount that it is desired the lower edge of the cuff be located above the ground. Thus, when the chalk mark is made on the trouser leg 38 in alignment with the notches 28 to indicate the location of fold 34 which forms the lower edge of the cuff, the said cuff is formed at exactly the right height.

For the great majority of men the standard placement of the trouser cuff is highly satisfactory. However, some men require that the cuff be located at greater or lesser distances from the floor. In such instances the chalk line 37 is made on trouser leg 38 above or below the top edge of bar 12 as shown by the dot-dash line in Fig. 2. This is accomplished by moving the block 15 upward the desired distance or by aligning the marking medium with one or the other of the notches 13.

In some instances it is desired to form imitation or French cuffs. These are formed as shown in Fig. 8. The material 33' of the cuff is folded upward at 34' which point locates the under edge of the cuff, extends upward and is folded downward again at 35'. The portion extending downward from point 35' extends only about half way to point 34' and a filler strip 40 is utilized to prevent creasing. For this arrangement the chalk mark for fold 34' is made at the notches 28 of the template, the mark for fold 35' is made at the edge 31 of slot 30, which is conveniently provided with a centrally located notch 59 and 75

a chalk mark is made at the other edge of the slot to indicate the point at which the material is to end.

Standard 10 is also utilized for marking the hem line of men's or ladies' overcoats or a lady's skirt. This is accomplished by setting the handle 24 at the desired height and marking the garment in alignment therewith.

The notch 25 identified by the letter B may be utilized in the tailoring of boys' trousers or ladies' slacks either in combination with a template 27 having an appropriately shorter upright or with the illustrated template which may be provided with a line 42 identified with the letter B and located the proper distance from the end edge of the upright thereof. This special arrangement for boys' trousers and ladies' slacks is occasioned by the inherent shortness of the legs thereof of boys' trousers.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. Tailor's apparatus for facilitating the accurate locating and forming of trouser cuffs on the bottom of trouser legs having suitably located chalk marks thereon, comprising an inverted substantially T-shaped template including an upright and cross-bar having notches at the junction of the upright and cross bar thereof and a longitudinal slot in the cross bar, the edge of said slot adjacent said notches being located half way between said notches and the far edge of the cross bar, said notches and said edges acting as guides in marking the trousers for the cuff folds, said upright from said notches to the end edge thereof being of a length to locate the cuffs the desired distance above the floor, the other edge of said slot rather than the far edge of the cross bar being used as a guide for marking a fold line for imitation cuffs, the end edge of the template upright being aligned with said chalk mark to locate the cuff folds accurately.

2. The combination of claim 1, wherein the upright is inclined a short distance forward of the junction with the cross bar.

JOSEPH SABATINI.
